LOCKING MEANS FOR TOTALIZERS

Herman F. Sadgebury, Dayton, Ohio, assignor, by
mesne assignments, to Central United National
Bank, Cleveland, Ohio, as trustee

Application July 17, 1931, Serial No. 551,506

4 Claims. (Cl. 235—130)

This invention relates to a locking means for a totalizer. It has frequently been found that unauthorized persons will maliciously attempt to change the amount set up on a totalizer by inserting a screw driver or other means to rotate the totalizer pinion. This might be done by a dishonest clerk. If he could set back the ten dollar totalizer wheel one point he would be enabled to knock-down \$10.00 and pocket the same and thereby perpetrate a fraud on the proprietor. The object of this invention is to provide a positive locking means to prevent such unwarranted manipulation.

For purpose of illustration I have shown the same in connection with that type of totalizer shown in the patent of Albert S. Wheelbarger and Grover C. Coil, No. 1,876,118, patented September 6, 1932.

In the drawings:

20 Figure 1 is a side elevational view of a machine such as shown in the said patent.

Figure 2 is a plan view of the totalizer.

Figure 3 is a side elevational view, partly in cross section, on the line 3—3 of Figure 2.

25 Figure 4 is a perspective view of the control member, and

Figure 5 is a perspective view of certain of the parts shown in Figure 3.

In the said patent the differential gears 1 are 30 rotatably mounted on a shaft 2 and the totalizer pinions 3 are moved into engagement with the differential gears on the adding operation and are disengaged therefrom on the return movement of the differential gears. This is accom-

35 plished by the rotation of a shaft 4, which is the main driving shaft, of the machine on which are mounted two cams 42 and 43 which are rotated in the direction of the arrow (Figure 1). The lever 44 is pivoted on a pin 45 and is urged to the left as viewed in Figure 1 by means of a spring 74 having its other end secured to the frame of the machine, which lever is provided with a roller 46. The upper end of the lever 44

40 is bifurcated and receives a pin 48 carried by a crank arm 49 securely mounted on a shaft 59, which shaft carries a crank arm 51 which carries a pin 52 received in a bifurcation in the end of the bell crank lever 53 pivoted on a shaft 54.

The lever 53 carries a pin 55 which is received 45 by an arm 56 rotatably mounted on the shaft 54. The arm 56 is an integral part of the holding member 57. A plurality of carrying arms 58 are

50 rotatably mounted on the shaft 54, each of which carrying arms is but an extension of a carrying 55 lever 47 which is provided with a carrying

nose 59. There are, of course, as many carrying levers as there are totalizer pinions 3 except that there is no carrying lever operated by the totalizer pinion of highest denomination. When one of the carrying levers 47 is in the position shown in Figure 5, the carrying nose 59 engages the totalizer pinion 3 with which it is associated and locks it against rotation in an anti-clockwise direction as viewed in Figure 3, but when the holding member 57 is elevated, raising the carrying lever 47, the said totalizer pinion will be free to rotate. A tripping lever 67 is pivoted on a cross bar 29, there being one such tripping pawl for each totalizer pinion. Each of the tripping levers 67 is provided with a shoulder 15 68 which will receive a laterally extending lug 63 on the carrying lever 47 when the said carrying lever is fully elevated. Each of the tripping pawls 67 is normally urged into the position shown in Figure 5 by means of a spring 69 connected 20 to a cross bar 60. Each of the tripping levers 67 is provided with a forwardly extending arm 70 terminating in a downwardly extending nose 71.

As soon as the shaft 4 commences its rotation 25 the cam 43 engages the roller 46 on the lever 44 moving the upper end thereof to the right as viewed in Figure 1. The cam 43 is provided with a lobe 5 which extends a short distance beyond the outer periphery of the cam 43. This lobe 30 moves the lever 44 the maximum distance in a clockwise direction as viewed in Figure 1, thereby by moving the arm 49 and shaft 50 rotating the arm 51 in an anti-clockwise direction as viewed in the said Figure 1, which elevates the arm 56 35 raising the holding member 57. The holding member 57 underlies and engages all of the carrying levers 47, raising them until the laterally extending lugs 63 are elevated beyond the shoulders 68 and the springs 69 move the said shoulders beneath the said lugs. Immediately thereafter the lobe 5 passes beyond the roller 46 and the carrying levers 47 are thereby permitted to descend a short distance, being pulled downwardly by means of the springs 61 which connect the carrying arms 58 and cross bar 60. The laterally extending lugs 63 now engage the shoulders 68. The lower ends of the tripping levers 67 are in the path of rotation of the carrying teeth 96. The carrying teeth are so positioned on the sides of the totalizer pinions 3 that they will engage the tripping levers 67 as soon as the totalizer pinions 3 pass beyond the position in which they would be when set to represent the numeral 9. It will, of course, be understood that there 55

is one such carrying tooth on each totalizer pinion. When the lobe 5 has passed beyond the roller 46 the said roller rides on the periphery of the cam 43 and the spring 74 holds the said roller in engagement with the periphery. This slight downward movement of the holding member 57 does not only allow the laterally extending lug 63 to engage the shoulder 68, as above mentioned, but the holding member 57 is held slightly below the carrying levers 47 so that if any of the carrying teeth should engage the tripping levers 67 and thereby remove the shoulder 68 from beneath its corresponding laterally extending lug 63, the spring 61 would move such lever 47 downwardly a short distance until it was stopped by the holding member 57. When the shaft 4 has practically completed its revolution, the roller 46 will roll off the cam 43 and the spring 74 will move the lever 44 to the left as viewed in Figure 7 and lower the holding member 57 so that the spring 61 can move the carrying nose 59 of the lever 47 into engagement with the totalizer pinion of next higher order and rotate it one notch provided, of course, that the carrying tooth 96 of the totalizer wheel of the lower denomination has engaged the tripping lever 67 and released its shoulder from beneath the laterally extending lug 63. The cam 42 engages a roller 73 rotatably mounted on a pin 72 carried by a lever 6 which is pivoted on the shaft 45. The lever 6 is urged to the left as viewed in Figure 1 by means of a spring 75. This lever carries a pin 76 at its outermost upper end, which pin is connected to a pin 77 on a crank lever 78 by means of a spring 79. The crank lever 78 is secured to a shaft 80, which shaft carries a plurality of crank arms 81 which are bifurcated at their upper ends and receive the shaft 27 carried by the frame members 25. It will be noted that the roller 73 does not engage the cam 42 until some little time after the cam 43 has engaged the roller 46. The object of this construction is to give the cam 43 sufficient time to elevate the carrying levers 47 and for the holding member 57 to drop slightly below its highest position after the roller 46 has passed the lobe 5. The cam 42 then engages the roller 73 and rocks the crank arms 81 inwardly or counter-clockwise as viewed in Figure 1 so as to move the totalizer frame to the left as viewed in the said figure so as to engage the totalizer pinions 3 with the differential gears 1, this movement being permitted by the slots 33 in the fixed frame 28, which slots engage the guide shaft 31. At approximately 180 degrees thereafter the cam 42 passes beyond the roller 73 and the spring 75 moves the totalizer frame and totalizer pinions to the right as viewed in Figure 1 so that the subtracting movement of the differential gears 1 will not be imparted to the totalizer pinions 3. A control member 7 is rotatably mounted on a shaft 8, which control member is provided with two V-shaped slots 9 and 10 and a rectangular shaped slot 11, all of which slots run substantially lengthwise of the control member 7; that is, the boundary line of the slot 9 nearest to the slot 11 is parallel with the long sides of the slot 11 and the boundary line of the slot 10 furthest removed from the slot 11 is parallel to the long sides of the slot 11 while the other long bounding side of the slots 9 and 10 extend at an angle to the sides of the slot 11. This relation between the slots 9 and 11 is very clearly shown in Figure 4.

A lever 12 is pivoted on the shaft 2 and is provided with a nose 13, the forward end of which is

blunt and the rear end of which is sloping. This nose extends within the slot 11 and is held therein by means of a spring 14 having its other end secured to a fixed pin 15 secured to the framework of the machine. A pin 16 is carried by a lever 17 pivoted on the shaft 24 which lever is provided with a nose 18 which engages a cam 19 on the shaft 20 on which the totalizer pinions are rotatably mounted. When the shaft 20 is reset counter-clockwise as viewed in Figure 1 the cam 19 elevates the lever 17 and pin 16, which pin, as shown in Figure 3, engages beneath a tail 21 of a yoke 22, which yoke overlies all of the arms 70, as well as levers 23 provided with tails 24 to which are secured springs 26, the spring 26 tending to keep the yoke 22 elevated above the arms 70 and levers 23 but when the machine is being reset the pin 16 would depress the yoke 22 and lower the arms 70 and levers 23.

Holding dogs 30 are pivoted on a shaft 32 and are provided with noses 34 which engage between the teeth of the totalizer pinions. The dog 30 is provided just above the nose 34 with a lug 35 on which is mounted a spring 36 which has its upper end anchored in a pin 37 on a bar 38 mounted on the shaft 29 and above a cross bar 39. The only function of this bar 38 is to provide a rigid support for the pin 37. The right hand end of the lever 23 is provided with a nose 40 which projects within a slot 41 of the control member 7.

There is only one lever 23 but there are as many tripping levers 67, arms 70, bars 38, carrying levers 47, and dogs 30 as there are differential gears 1.

In operation the parts are normally as shown in Figure 3. The noses 62 of the holding dogs 30 are closely adjacent to the outer periphery of the control member 7 and the nose 34 of each of the holding dogs positively locks each of the totalizer pinions against rotation in any direction. The operator may insert a screw driver and attempt to rotate these totalizer pinions or any one of them but he simply forces the nose 62 against the periphery of the holding member 7 but he has not succeeded in removing the nose 34 of each of the dogs from engagement between the teeth of the pinions and they, therefore, cannot be rotated. He can, however, reset the totalizer pinions by rotating the shaft 26 by any suitable means which form no part of this invention and is, therefore, not shown, which will rotate the cam 19 and elevate the lever 17 and pins 16 which extend beneath the tail 21 of the yoke 22 which extends over the lever 23 and over all of the arms 70, thereby depressing the said lever 23 and arms 70. As the lever 23 is depressed, since its nose 40 engages in the slot 41, it will rotate the control member 7 anti-clockwise as viewed in Figure 3 so that the slot 10 will be beneath the noses 71 of the arms 70 and the slot 9 will be adjacent the noses 62 of the dogs 30. Since the dog 30 is now only yieldingly held against the totalizer pinions and does not lock them, the totalizer pinions can be rotated. As this rotation occurs the totalizer wheels may, therefore, be reset in the conventional manner.

In the normal adding operation of the machine it will be remembered that the totalizer pinions are moved into mesh with the differential gears 1 at the commencement of the operation of the machine. The left hand end of the lever 12 (Figure 3) engaging in the slot 11 will rotate the control member 7 so as to bring the slot 10 beneath the noses 71 of the arms 70 and to bring the slot 9 adjacent the noses 62 of the dogs 30. It will also be remembered that the lobe 5 of the cam

43 has elevated the lugs 63 of the carrying levers 47 so that they are engaged above the shoulders 68 of the tripping levers 67 and that as soon as the lobe 5 passes the roller 46 the holding member 57 is slightly lowered. If the differential gears are now operated, being in mesh with the pinions 3, the pinions 3 will be thereby actuated and it may be that a carrying operation will be necessary. If there is any carrying, the pinion of lower 10 denomination, having a carrying tooth 96, will engage the tripping lever 67 and move it to the left as viewed in Figure 3 so as to release the shoulder 68 from beneath the lug 63 and the carrying lever 47 will then drop a short distance until it 15 is stopped by the holding member 57, which distance is not sufficient to carry to the totalizer pinion of next higher order. If the carrying tooth 96 moves the tripping lever 67 as just described, the nose 71 of the arm 70, which is integral with 20 the tripping lever 67 will be forced into the slot 10 by the carrying tooth 96. At the end of the adding operation, but before the carrying has taken place, there may be none or any number of the noses 71 extending within the slot 10, depending upon how many totalizer pinions have 25 passed the carrying point. Towards the end of the operation of the machine the totalizer pinion is withdrawn from the differential gears as heretofore described and shortly thereafter the 30 cam 43 passes beyond the roller 46 and the holding member 57 is permitted to fall to its lowermost position so that the carrying noses 59 of any of the carrying levers 47 which have been released by the carrying tooth 96, releasing the tripping 35 lever 67, will engage the pinion of next higher order and rotate it one point, thereby carrying. It may sometimes be, however, that this carrying of 1 will have to be carried through a number of the totalizer pinions. For instance, if 1 is added to 999, not only do we have to carry from units to tens, but from tens to hundreds and from hundreds to thousands. In the above example, only the units carrying tooth 96 would have released the carrying lever 47 which would actuate the 40 tens counter on the carrying operation and all of the other carrying levers 47 would be retained in their elevated position; that is, with the nose 63 engaging the shoulder 68. When, however, the tens wheel is rotated, as just mentioned, its carrying tooth 96 would engage a tripping lever 67 and would release its carrying lever 47 which would carry to the hundreds. This requires, however, that the arms 70 should be permitted to enter the slot 10 and it will be remembered that the lever 12 will no longer be holding the control member 7. However, in the above example, the tens nose 71 would be engaged in the slot 10 and when it is released by the carrying tooth 96 passing beyond the lever 67 and the hundreds wheel 45 is now moving, the nose 62 of the dog 30 would be in the slot 9, which thereby holds the control member 7 against moving back to its initial position. It is this alternate movement of the noses 71 and 62 into and out of the slots 10 and 9 that 50 keeps the control member from being rotated back

to its normal position. The slots are made V-shaped so as to assure that the noses would readily enter the slots and not strike against the side thereof so that the control member 7 during the various carrying operations would act somewhat as an escapement member moving progressively towards its normal position as succeeding transfers occur. When all of the noses 71 are released from the slot 10, the spring 26 pulls the lever 23 upwardly and thereby rotates the control member back to the position shown in Figure 3. 10

It is obvious that many changes may be made in the specific form of the invention shown in this application and I, therefore, desire to claim the same broadly except as I may limit myself 15 in the appended claims.

Having now described my invention, I claim:

1. In a machine, a plurality of totalizer wheels, actuating means therefor, means to move said totalizer wheels into engagement with said actuating means, a rotatable control member having a groove therein, a plurality of locking means normally engaging the periphery of said control member and engaging each of said totalizer wheels, thereby locking said totalizer wheels 20 against any additive or subtractive movement, means to rotate said control member when the totalizer is being moved into engagement with its actuating means so as to bring said slot adjacent the locking means to free all of the locking means 25 from locking engagement with the totalizer wheels. 30

2. In a machine, a plurality of totalizer wheels, a carrying tooth on each of said totalizer wheels, a rotatable control member provided with a slot, 35 a plurality of levers, there being one lever for each carrying tooth, each of said carrying teeth engaging and actuating said lever when said carrying tooth passes from 9 to zero, a nose carried by each of said levers and adapted to be moved into said slot when said lever is actuated, and means to carry to the wheel of next higher order. 40

3. In a register, a control member provided with a plurality of slots, totalizer wheels, means whereby said control member normally locks said totalizer wheels against movement, differential members to engage and actuate said totalizer wheels, means to rock said control member as the totalizer wheels are being brought into mesh with the differential members, and means to restrain said control member from being moved back into its normal position until after all carrying operations have been completed. 45

4. In a register, a control member provided with a plurality of slots, totalizer wheels, means whereby said control member normally locks said totalizer wheels against movement, differential members to engage and actuate said totalizer wheels, means to rock said control member as the totalizer wheels are being brought into mesh with the differential members, and means to return 60 the control member to its normal position after all carrying operations have been completed. 55

HERMAN F. SADGEBURY.
